UNITED STATES PATENT OFFICE

FRANK J. ABEL, OF NEW YORK, N. Y., ASSIGNOR TO SUN RISE LAMP MFG. CO., INC.,
A CORPORATION OF NEW YORK

DESIGN FOR AN ILLUMINATED BASE FOR CLOCKS OR ARTICLES OF ANALOGOUS NATURE

Application filed February 6, 1930. Serial No. 34,443. Term of patent 3½ years.

To all whom it may concern:

Be it known that I, FRANK J. ABEL, a citizen of the United States of America, and a resident of the city of New York, in the county of Bronx and State of New York, have invented a new, original, and ornamental Design for Illuminated Bases for Clocks or Articles of Analogous Nature, of which the following is a specification, reference being had to the accompanying drawing, forming a part hereof.

Figure 1 is a front perspective view of an illuminated base for clocks or articles of analogous nature showing my new design; and

Figure 2 is an end elevational view of the same.

The dominant feature of the design resides in the provision of two lamp-receiving enclosures A—A made from glass panels and separated a substantial distance from one another to accommodate a clock frame illuminated thereby.

I claim:

The ornamental design for an illuminated base for clocks or articles of analogous nature substantially as shown and described.

FRANK J. ABEL.
